LOAD AND FIRE MECHANISM

Edward Wild, West Hartford, Conn., assignor to
Veeder-Root Incorporated, Hartford, Conn., a
corporation of Connecticut

Application July 30, 1940, Serial No. 348,424

7 Claims. (Cl. 74-2)

The present invention relates to a load and fire mechanism adapted to multiply the movement or power of one part and transmit it to another part.

Although capable of other uses, the load and fire mechanism is here shown as used in conjunction with a cutmeter or predetermined counter of the type disclosed in Patent No. 2,159,314, issued May 23, 1939, to Harvey N. Bliss. The counter described in said patent is commonly used on looms and is adapted, after a predetermined yardage of material has been woven, to operate a plunger and, through a Bowden control wire, actuate the stop mechanism of the loom. In some instances, the distance of travel of the plunger or the power transmitted is not sufficient to assure positive movement of the control wire, and the loom stop mechanism fails to operate.

One purpose of the load and fire mechanism disclosed herein is to increase both the power transmitted by the plunger and the distance of movement of the control wire, thus assuring positive operation of the stop means.

Another purpose is a load and fire mechanism which is extremely simple in construction, consists of a minimum number of parts, is positive in operation, and may be readily and inexpensively manufactured.

Other objects will be in part obvious and in part pointed out more in detail hereinafter.

The invention accordingly consists in the features of construction, combination of elements, and arrangement of parts which will be exemplified in the construction hereafter set forth and the scope of the application of which will be indicated in the appended claims.

In the accompanying drawing:

Figure 1 is a view of the load and fire mechanism embodying the invention herein shown assembled with a cutmeter or predetermined counter;

Fig. 2 is a sectional view showing the load and fire mechanism in fired position; and

Fig. 3 is a sectional view showing the load and fire mechanism in firing or loaded position.

Referring to the drawing, there is shown a cutmeter A of the type disclosed in the above-mentioned Bliss patent and including a plunger 10 slidable in a bushing 11 and adapted to be depressed by a trigger 12. Means are provided in the counter for releasing the trigger 12 after a predetermined count has been registered, but as these means form no part of the invention herein and are fully described in the above-

indicated Bliss patent, no further reference thereto will be made.

The load and fire mechanism incorporating the invention herein is generally designated at 5 B and includes a substantially cylindrical open ended casing 14 having a centrally disposed bore 15. The casing is closed at its lower end by a cap or closure 16 and at its upper end with a threaded opening 18 for securing it to the threaded bushing 11 in which the cutmeter plunger 10 operates.

Mounted within the bore 15 is a piston 22 of like diameter to a reduced central portion 23 of the bore whereby the piston is maintained in 15 vertical and aligned position. Piston 22 is normally urged to bottom or fired position by a heavy firing spring 24 disposed between a flange 26 on its lower end and a downwardly facing shoulder 28 of the casing bore 15 formed by enlarging the 20 diameter of a lower portion 29 of the bore. The bottom face of the piston 22 also has a central opening 22a in which there is secured the end 25 of a control wire 54, such as the loom stop mechanism. The wire extends through a protective sheathing 56 secured in an opening 16a provided in the cap 16 and transfers the movement of the piston to a remote point while the other end of the wire (not shown) is connected, such as the stop mechanism of a loom.

30 To raise the piston to firing or loading position, it is provided with a rack 30 engageable with a gear 32 mounted on a shaft 34 journalled in the casing 14. The shaft 34 extends outwardly of the casing and carries a wing nut 36 35 for rotating the shaft and raising the piston 22 to place the firing spring 24 under compression. When so raised, means are provided for releasably maintaining the piston in cocked position; these means comprising a latching plunger 33 40 slidably mounted in an open top bore 35 in piston 22 and a ball stop 37 seated in an opening 40 extending through the piston wall.

The latching plunger 33 includes a lower portion 41 of like diameter to the bore of the piston and a reduced upper portion 42 connected to the lower portion by a downwardly tapering camming shoulder 44. The lower portion 41 is hollowed out to receive a light spring 46 which normally tends to urge the plunger out of the piston. To prevent the plunger from being released from the piston, the stop ball 37 is of a greater diameter than the thickness of the wall of the piston, whereby when the latter is in its fired position the ball will be urged inwardly to

overlie the camming shoulder 44 of the plunger and maintain it in its lowermost position.

However, when the piston 22 is moved to firing position, the ball receiving opening 40 will be moved into an enlarged portion 48 of the bore 15 wherein the diameter is such that the shoulder 44 of the plunger, due to the pressure of spring 46, will cam the ball partially through opening 40 to a position where it will overlie an upwardly facing shoulder 50 and hold the piston 23 in raised position and load spring 24. When in this position, the upper end 52 of the plunger 33 will also engage the lower end of the cutmeter plunger 10 and hold same in raised position until the cutmeter has again counted to its predetermined count. When this occurs, the trigger 12 will force the cutmeter plunger 10 downwardly, which, in turn, will force the plunger 33 downwardly until the camming shoulder 44 is lowered sufficiently to release the ball stop 31, whereupon the firing spring 24 will force the piston 22 to fired position.

It is obvious from the foregoing that by properly positioning the latching means within the piston the length of stroke of the piston 22 may be varied, and by varying the strength of the spring 24 the power transmitted thereby may be varied. In this manner, any desired movement of the control wire or amount of power necessary to be delivered thereby may be readily obtained.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In a load and fire mechanism of the character described, a casing, a piston slidably mounted in the casing, spring means normally urging the piston to fired position, means for moving the piston to firing position to load the spring, and latching means including a ball automatically operable upon movement of the piston to firing position, said ball directly engaging and releasably interlocking said piston and said casing in firing position.

2. In a load and fire mechanism of the character described, a casing, a piston slidably mounted in the casing, spring means normally urging the piston to fired position, and latching means including a ball automatically operable to maintain the piston in firing position upon movement of the piston to firing position, said ball directly engaging and releasably interlocking said piston and said casing in firing position.

3. In a load and fire mechanism of the character described, a casing, a piston slidably mounted in the casing, spring means normally urging the piston to fired position, a latching plunger slidably mounted in the piston, spring means normally urging the plunger out of the piston, a ball engageable with the plunger for retaining said plunger in the piston when the latter is in fired position, said ball directly engaging and releasably interlocking the piston in firing position when the latter is moved thereto.

4. In a load and fire mechanism of the character described, a casing, a piston slidably mounted in the casing and movable between fired and firing positions, spring means normally urging the piston to fired position, a latching plunger slidably mounted in the piston, spring means normally urging the plunger out of the piston, stop means for retaining the plunger in the piston when the latter is in fired position and comprising a ball positioned in an opening in the piston and overlying a camming surface on the plunger.

5. In a load and fire mechanism of the character described, a casing having a bore therein, said bore having one section of reduced diameter, a piston slidably mounted in said section, spring means normally urging the piston to fired position, a latching plunger slidably mounted in the piston, spring means normally urging the plunger out of the piston, stop means for holding the plunger within the piston when in fired position and comprising a ball positioned in an opening in the piston wall and overlying a camming surface on the plunger when said piston wall opening is aligned with the reduced diameter of the bore when the piston is in fired position, means for moving said piston to firing position whereby said piston wall opening will be aligned with a larger diameter of the bore and said plunger will urge said ball stop outwardly to overlie a shoulder in the casing wall and restrain said piston in firing position.

6. In a load and fire mechanism of the character described a casing having a bore provided with a shoulder, a piston slidably mounted in the casing bore and having a radially disposed opening therein, spring means normally urging the piston to fired position, a latching plunger slidably mounted in an inner bore provided in the piston, a camming surface on the plunger, spring means normally urging the plunger out of the piston and stop means for holding the plunger within the piston when in fired position, said stop means comprising a ball positioned in the opening in the piston wall and overlying the camming surface on the plunger, means for simultaneously moving said piston, plunger and ball to firing position, said movement of the plunger aligning said piston opening with the shoulder in the casing bore whereupon said plunger spring means will move said plunger relative to the piston and cam said ball to a position overlying said shoulder whereby the piston will be retained in its firing position.

7. In a load and fire mechanism of the character described, a casing having a bore provided with an upwardly facing shoulder, a piston having an internal bore therein and an opening through the wall thereof, said piston being operably supported within said casing bore and movable between firing position where said wall opening is in alignment with the upwardly facing shoulder of the casing bore and fired position where said opening is out of alignment with said shoulder, spring means normally tending to urge said piston to fired position, a bore positioned within said opening, a plunger within said piston bore movable between two positions and held in one position by said bore when the piston is in fired position and spring means for moving said plunger to its second position when the piston is in firing position to cause said plunger to remove the bore through the opening to overlie said upwardly facing shoulder and retain the piston in firing position.
